CLAIM

The ornamental design for a multi-textured reversible bedding device, as shown and described.

DESCRIPTION

FIG. 1 is a top perspective view of a multi-textured reversible bedding device, showing the new design.

FIG. 2 is a bottom perspective view showing the multi-textured reversible bedding device of FIG. 1.

FIG. 3 is a top plan view of the multi-textured reversible bedding device of FIG. 1; and,

FIG. 4 is a bottom plan view of the multi-textured reversible bedding device of FIG. 1.

The multi-textured reversible bedding device is shown with a symbolic break in its width. The appearance of any portion of the article between the break lines forms no part of the design.
